UNITED STATES PATENT OFFICE.

JACOB BENSING, OF MALINTA, OHIO.

BRICK AND TILE CUTTING MACHINE.

No. 853,573.

Specification of Letters Patent.

Patented May 14, 1907.

Application filed August 23, 1906. Serial No. 331,705.

To all whom it may concern:

Be it known that I, JACOB BENSING, a citizen of the United States, and a resident of Malinta, in the county of Henry and State of Ohio, have invented certain new and useful Improvements in Brick and Tile Cutting Machines; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to machines for automatically cutting tile, brick or other products from one or more columns of clay or other plastic material as the same is continuously forced from the die or dies of a mill, and has particular reference to improvements on the machines covered by my former United States Letters Patent Nos. 411,638, 524,302, 563,252, 621,315, 718,077 and 801,639, granted to me, respectively, September 24, 1889, August 14, 1894, July 7, 1896, March 21, 1899, January 13, 1903, and October 10, 1905.

The object of my present invention is to cheapen, simplify and improve upon the cutter-guiding means disclosed in my previous Letters Patent by the provision of means in association with the cutter-arms and their cutter-wires whereby the revolving movement of the cutter-arms will cause each cutter-wire, as it ascends in advance of the column end after a cut, to move out of contact therewith so as not to mar or injure the squareness of its surface, as would be the case were the cutter-wire to have sliding contact therewith on its ascending movement after a cut.

Further objects of my invention as well as the operation, construction and arrangement of the parts thereof will be apparent by reference to the following specification and the accompanying drawings, in which,—

Figure 1 is a vertical longitudinal section of the cutting-machine embodying my invention, with only a part of the carrier and cutter-arms shown. Fig. 2 is a perspective view of one of the carrier sections and associated cutter-arm guides used with my improvement. Fig. 3 is a central section of a carrier-section and brick illustrating the relative lines of movement of a cutter-wire in

its descent and ascent. Fig. 4 is a front elevation of the cutter-wheel and two associated cutter-arms, and Fig. 5 is a side view of the guide-roll spindle of a cutter-arm, with the associated guide-roll and carrying arm shown in section.

Referring to the drawings, 1 designates one side of my machine, which side has the endless grooved way or track 2 provided on its inner wall in which the anti-friction rollers 3 of the contiguous side of the endless carrier 4 operate. The sections of the carrier are shown as comprising the two spaced base members 5, which are connected together by the carrier-bar 6 and are formed with the rearwardly-disposed dependent single lugs 7 and the forwardly disposed dependent double lugs 8, which carry the spindles for pivotally connecting the double lugs to the single lug of the next carrier-section and also carry the rollers 3. Rising from the forward outer portion of the bases 5 of each section are the vertically-disposed guide-standards 9, which comprise two spaced parallel arms 80 the upper ends of which describe a quarter circle outwardly from each other so as to abut the end of and form a semi-circle with the contiguous arms of the section next ahead and to the rear when the sections are on a straight portion of the track, as shown in Fig. 1. The arms of each standard are braced at their upper ends by a yoke or U-shape member 10, which is horizontally positioned at the outer side thereof to permit the guide-rollers of the cutter-arms hereinafter described to freely descend and ascend between the arms of a standard. The standards 9 are so disposed relative to their carrying sections as to position the central line of the space between their arms in substantial radial alinement with the axis of the rollers of the carriers.

Revolutionally mounted above the carrier 4 on a transverse shaft 11 is the cutter-wheel 12, which has a plurality of U-shaped cutter frames 13 pivotally attached to its rim, as at 14, for a limited oscillatory movement relative thereto, as more fully set forth in my former Letters Patent No. 718,077. The terminals of the arms of the cutter-frames 13 are each formed with a transverse bearing 15 in which is mounted a spindle 16, the same being held in fixed position relative thereto by a set-screw 17. Carried at the outer end of each spindle 16 is a roller 18, which is retained thereon by a nut 19 and is adapted to

operate between the arms of the guide-standards 9 so as to guide the cutter-frame as a cut is being made by its wire. The inner end of each spindle is formed with a head 20, which is provided at its end with an annular flange or disk-like portion 21 under which the cutter-wires 22 are passed. These cutter-wires lie within notches 23 provided in the outer peripheral portions of the head flanges 21 of the opposite spindles of a frame and have their ends passing inwardly diametrically across the inner faces of such flanged portions, the heads 20 of the spindles being cut away, as at 24, for such purpose, and secured to suitable securing means 25 on the frame arms. The notch 23 of each spindle is disposed in the outer peripheral portion of its flange 21 relative to the associated frame arm and its depth is less than that of the radius of the flange, thus positioning the span of the cutter-wire at a greater radius from the cutter-wheel center than is the axis of the spindle 16 and guide-roller 18, as shown in Figs. 3 and 5. This positioning of the cutter-wires relative to the axis of the guide-rollers 18 of the cutter-frames causes them to move in different planes as they descend and ascend between the arms of the guide-standards 9, the wire reaching a central point between the arms of a standard when at its limit of downward movement, as illustrated by the dotted lines $x-y$ in Fig. 3. In order that the clay column 26 shall be given a square cut by each cutter-wire as it passes therethrough on its descending movement the guide standards 9 are inclined forwardly at a sufficient angle to the surface of the carrier-bars 6 of the associated carrier-sections to compensate for the angle described by the descent of a wire relative to a perpendicular during the cutting action, thus causing a wire to follow a perpendicular plane in its descent through the column and a plane at an angle to the cut end of the column on its descending movement, which plane of ascent is in substantially the same position relative to the forward guide-arm as the plane of descent is to rear guide-arm of a standard, as represented by the lines $x-y$ in Fig. 3, the dotted line z thereof designating the central line of the standard. This feature of my invention is of special importance to the operation and construction of machine of this class due to the fact that a positive guiding of the cutter-wires in their descending and ascending movements through the clay-column is effected and the construction of the carrier is simplified and lightened. While in my former Letters Patent aforesaid the cutter-wires have been positively guided in their descending or cutting movements by the action of the guide-standards of the carrier, there was no provision made for positively guiding the wires in their ascending movements after making a cut thereby rendering them liable

to bound away from their supposed planes of movement and have contact with the surface of the cut block or section 26^a next ahead whereby to injure the surface of the end thereof. With my present construction the arms of the guide-standards of the carrier are parallel to each other and are spaced only sufficiently apart to permit free descending and ascending movements of the guide-rollers 18 therebetween, thus rendering it possible for the ends of the cutter-frames to have only a very slight lateral movement relative to the guide-standards, the movement of the cutter-wires away from the face of the column end so as not to mar the surface thereof on their ascending movements being effected by positioning the wires as above described so that they have an angular movement outwardly from the column end as illustrated by the line y in Fig. 3. With my improved construction the endless carrier is also made lighter due to the lightening of the guide-standards thereof over those heretofore used, thus requiring a less amount of power to move the carrier and operate the machine, which is of considerable importance in machines of this class.

The operation of my invention is as follows: As the cutter-wire of a cutter-frame descends through the clay column 26 it is positively guided by the guide-standards 9, the inclination of which is sufficient to compensate for the angular movement of the wire relative to a perpendicular plane due to its being offset outwardly from the axes of the guide-rollers 18 of the cutter-frames, so that a right-angled cut of the column will be made. On the completion of the cut, the carrier-section carrying the block thus severed is caused to tip slightly forward due to its passing upon a declined portion of the track 2, thus effecting a separation of the contiguous block ends to form a space therebetween for the ascending wire to pass through as shown in Fig. 1. As the wire ascends, its position relative to the axes of the guide-rollers 18 causes it to move outwardly from contact with the end of the succeeding block, as indicated by the dotted line y in Fig. 3, but not sufficiently to have contact with the end of the preceding block whereby to mar its surface, and it is positively guided in such ascending movement by the parallel arms of the associated guide-standards 9.

Having thus described my invention, what I claim as new and desire to secure by Letters Patent, is,—

1. In combination, a revoluble cutter-frame having guide-members at its extremities, a cutter-wire carried by the cutter-frame and off-set outwardly from the axes of the guiding-members, and an endless carrier comprising a plurality of pivotally connected sections each having a U-shaped guide standard inclined slightly from a perpendicular

and adapted to effect a positive guiding of the cutter-wire both in its descending and ascending movements through a column.

2. In combination, a revoluble cutter-frame having guide-rollers at its ends, a cutter-wire carried by the cutter-frame and disposed at a greater radius from the axis of the cutter-frame than the axes of the guide-rollers, and an endless carrier comprising a plurality of flexibly connected sections each having a U-shaped guide standard at either end for coöperating with the guide-rollers, the upper terminals of which standards curve outwardly to abut the terminal of the standard of the contiguous section, said standards being slightly inclined from a perpendicular to cause the cutter-wire to follow a perpendicular course in its cutting movement and to move out of contact with the column end in its ascending movement.

3. In combination a revoluble cutter-frame, guide-rollers carried at its extremities, a carrier having guide-standards associated therewith to coöperate with the guide-rollers of the frames to guide the frame extremities during a cutting and subsequent ascending movement, a cutting element carried at the extremities of the cutter-frame and having a greater radius than that of the axes of the guide-rollers relative to the axis of the cutter-frame whereby the cutting-element will have different planes of movement when making a cut and ascending therefrom.

4. In combination a revoluble cutter-frame, guide-rollers carried thereby, a cutter-wire carried by the cutter-frame and having a greater radius than that of the axes of the guide-rollers relative to the axis of the cutter-frame, and a carrier having members for coöperating with the guide-rollers of the frame to guide their cutting and subsequent

ascending movements, said members being slightly inclined from a perpendicular relative to the carrier whereby to cause the cutter-wire to have a perpendicular cutting movement and an angled ascending movement after a cut.

5. The combination with a carrier having guide-standards inclined from a perpendicular relative to the attached carrier-section, of a revoluble cutter having a plurality of attached cutter-frames each carrying a cutter-wire and guide-rollers for coöperating with the guide-standards of the carrier, said cutter-wires having different radii than the axes of the guide-rollers relative to the axes of the cutter, whereby the cutter-wires have angular descending and ascending movements when making a cut.

6. The combination with a carrier having guide-standards provided with spaced parallel guide-arms, of a revoluble cutter carrying a plurality of U-shaped cutter-frames, a spindle fixed at the end of each frame arm and having its inner end formed with a flange provided with an outwardly disposed notch the depth of which is less than the radius of the flange, a guide-roller carried by each spindle to coöperate with the guide-standards of the carrier, and a cutter-wire spanning each cutter-frame and engaging the notches in the associated spindles whereby it is offset from the axes of the guide-rollers, substantially as described.

In testimony whereof I have hereunto signed my name to this specification in the presence of two subscribing witnesses.

JACOB BENSING.
